UNITED STATES PATENT OFFICE.

GRAHAM CLARKE, OF CLEVELAND, OHIO.

BOTTLE FOR CONTAINING LIQUIDS OR GASES UNDER HIGH PRESSURE.

SPECIFICATION forming part of Letters Patent No. 660,326, dated October 23, 1900.

Application filed August 31, 1899. Serial No. 729,066. (No model.)

To all whom it may concern:

Be it known that I, GRAHAM CLARKE, a citizen of the United States, and a resident of Cleveland, county of Cuyahoga, and State of Ohio, have invented a new and useful Improvement in Bottles for Containing Liquids or Gases Under High Pressure, of which the following is a specification, the principle of the invention being herein explained and the best mode in which I have contemplated applying that principle so as to distinguish it from other inventions.

My invention relates to improvements in means for containing liquids or gases under high pressure and for controlling the flow of same, the object being to secure an economically-constructed receptacle for containing such liquids or gases provided with a valve absolutely controlling the flow of same without the use of packing, whereby all possible loss of the contents through leakage is prevented.

Said invention consists of means hereinafter fully described.

The annexed drawings and the following description set forth in detail certain mechanism embodying the invention, such disclosed means constituting but one of various mechanical forms in which the principle of the invention may be used.

In said annexed drawings, Figure I represents a side elevation of the upper portion of a liquid or gas containing bottle embodying my invention. Fig. II represents a vertical axial cross-section of same.

The invention consists of a metal (usually steel) bottle A, which is drawn so as to form an integral neck a, in which is transversely located an integral wall a', having a central axial fluid-opening a², said neck forming a support or body portion for a closure-valve of improved construction. Said neck is bored and counterbored so as to form a shoulder a³. The center of the bottom of the counterbore 45 is bored to receive a hard-rubber valve-seat b, having a flat upper surface and an axially-located duct or fluid-opening b', communicating and registering with the duct a². The up-

per surface of said seat is raised and is substantially in the same plane with the upper 50 surface of shoulder a³, thereby forming an annular space a⁴ between said shoulder and valve-seat. Resting upon said shoulder is an imperforate diaphragm d, whose rim is secured upon the shoulder a³ by means of a 55 jam-nut e, having threaded engagement with the neck of the bottle, as shown. Said nut is formed with an inner axial bore e' and provided with a set-screw f, communicating with said bore e'. Said screw is formed with an 60 inner axial bore f', as shown. A plunger g, formed with a teat g', rests upon the middle of the diaphragm, the teat projecting into the screw-bore. The plunger being, as above described, intermediate with respect to the 65 screw f and the diaphragm, it is seen that the depression of said nut will cause the inner end of the bore f' to engage the teat and press the diaphragm down upon the valve-seat and securely close the opening therein. An outlet-duct a⁵ is formed in the body of the neck and communicates with the annular space a⁴. On the release of the plunger by the outward movement of the screw the pressure of gas or liquid in the bottle raises the diaphragm and 70 permits the escape of the contents of the bottle as desired. The diameter of the teat and body of the plunger are made such as to permit of rotative movement of the plunger in the nuts f and e, whereby the rotation of the 75 plunger upon the diaphragm is prevented and said diaphragm preserved from injury.

Other modes of applying the principle of my invention may be employed instead of the one explained, change being made as regards 80 the mechanism herein disclosed, provided the means covered by the following claim be employed.

I therefore particularly point out and distinctly claim as my invention—

The combination of the bottle A formed with the integral transverse wall a' formed with a central opening, the valve-seat b formed with the opening b' registering with said central opening, the diaphragm d supported by the 85 shoulder a³ formed in the bottle-neck, the 90

jam-nut *e* for securing said diaphragm upon said shoulder and formed with the bore *e'*, the set-screw *f* communicating with said bore formed with the bore *f'*, and the plunger *g* located in bore *e'* and formed with the teat *g'* projecting into bore *f'*, said neck formed with the opening *a⁵* communicating with the annular space intermediate of said raised valve-

seat and said shoulder, substantially as set forth.

Signed by me this 28th day of August, 1899.

GRAHAM CLARKE.
